UNITED STATES PATENT OFFICE

166,732

TWIN BED UNIT

Thomas Francis Carey, Kensington, Md.

Application September 17, 1951, Serial No. 16,668

Term of patent 7 years

(Cl. D5—4)

To all whom it may concern:

Be it known that I, Thomas Francis Carey, a citizen of the United States, residing at Kensington, in the county of Montgomery and State of Maryland, have invented a new, original, and ornamental Design for a Twin Bed Unit, of which the following is a specification, reference being had to the accompanying drawing, forming a part hereof.

The figure is a perspective view of a twin bed unit showing my new design.

The side of the bed unit not disclosed is substantially the same in appearance as the side shown in the drawing figure.

I claim:

The ornamental design for a twin bed unit, substantially as shown and described.

THOMAS FRANCIS CAREY.
